UNITED STATES PATENT OFFICE.

PAUL M. RAINY, OF GLEN RIDGE, NEW JERSEY, ASSIGNOR TO WESTERN ELECTRIC COMPANY, INCORPORATED, OF NEW YORK, N. Y., A CORPORATION OF NEW YORK.

PRINTING-TELEGRAPH SYSTEM.

1,367,717.

Specification of Letters Patent.

Patented Feb. 8, 1921.

Application filed November 15, 1917. Serial No. 202,103.

To all whom it may concern:

Be it known that I, PAUL M. RAINY, a citizen of the United States, residing at Glen Ridge, in the county of Essex and State 5 of New Jersey, have invented certain new and useful Improvements in Printing-Telegraph Systems, of which the following is a full, clear, concise, and exact description.

This invention relates to printing telegraph systems, and particularly to multiplex systems of the secret service type.

The principal object of this invention is to provide a printing telegraph system whereby messages may be sent from one station 15 to another in a code unintelligible to receiving operators at stations connected on the line for whom the messages are not intended.

A further object is to provide an efficient 20 and reliable system and one which will provide a high degree of secrecy between authorized stations.

For the accomplishment of the above objects, the invention contemplates the employment of a five-unit code, consisting of 25 positive and negative impulses, similar to the well-known Baudot code, except that the marking impulses, or the impulses required to operate the receiving mechanisms, are arranged in different code combinations for 30 each transmitter and each channel of communication. However, the invention is not limited to any particular code or to any particular kind of impulses. More specifically, 35 one of the preferred forms of the invention as herein shown, comprises a full quadruple multiplex telegraph system arranged for eight channels of transmission with the transmitters and receivers so arranged that 40 a message sent out by any transmitter can be received intelligibly by only one receiving mechanism or by the particular receiver for which the message is intended. For example, as illustrated in Figure 2 of the accompanying drawings, the five transmitter 45 contacts of the transmitter connected to the first quadrant as shown developed, may be normally connected to + - - - -; the transmitter contacts of the transmitter connected to 50 quadrant #2, may be normally connected to + + - - -; the transmitter contacts of the transmitter connected to quadrant #3, may be normally connected to + + + - -; etc., and the selecting mag- 55 nets of the receiving mechanism connected

to the corresponding quadrants at the receiving station may be arranged as shown so that the respective magnets will respond to the actuation of the respective transmitter contacts. This arrangement provides a 60 different code combination of signaling impulses for each set of transmitting and receiving instruments. The transmitter contacts of each transmitter are so arranged that when the transmitters are idle, or when 65 they are not sending message impulses, they will send no impulses over the line which will cause the operation of the selecting mechanism at the receiving stations. In other words, the transmitter contacts are 70 normally connected to spacing battery.

The above and other features of this invention will be fully set forth in the following description and claims, and will be more readily understood by reference to the 75 accompanying drawings, in which only so much of the system as is necessary for a complete understanding of the invention is shown diagrammatically.

Fig. 1 represents a multiplex telegraph 80 system comprising stations A and B connected by a transmission line L; and Fig. 2 shows the sending rings of station A and the receiving rings of station B developed, with the sending segments connected to 85 transmitter contacts and the receiving segments connected to selecting magnets.

At stations A and B are shown the well-known types of rotary distributors which may be driven in any suitable manner as 90 by a motor. The distributor 10 at station A consists of a pair of sending rings 12 and 14, a pair of receiving rings 16 and 18 and a trailer or brush arm 20. One ring of each pair is continuous and the other seg- 95 mented. The trailer arm 20 carries brush 22 for connecting the sending segments of ring 14 with the continuous ring 12, and brush 24 for connecting the receiving seg- 100 ments of ring 18 with the continuous ring 16. The continuous sending ring 12 is connected to the line L in the usual manner through a polar relay 26 provided with the usual duplex balance. The continuous re- 105 ceiving ring 16 is connected to a pole-changing tongue 28 of relay 26. It is of course understood that the tongue 28 of line relay 26 is not operated by the impulses sent over the line from station A, but is operated by the impulses received over the 110

line from station B. The distributor 110 and line relay 126 at station B are identical and function in the same manner as the corresponding apparatus at station A, and 5 therefore no further description of the apparatus at station B is deemed necessary.

In Fig. 2 the four quadrants of the sending rings at station A and the four quadrants of the receiving rings at station B are 10 shown developed. The sending segments of each quadrant are shown connected to transmitter contacts and the latter contacts are shown in their idle positions. The receiving segments of each quadrant are shown connected to the selecting magnets of the receiving mechanism and are arranged to respond respectively to changes in current polarity caused by the actuation of the transmitter contacts connected to sending segments 15 corresponding with the respective segments to which the selecting magnets are connected. Any suitable means may be provided for maintaining synchronism between the distributors, such, for example, as disclosed in my copending application Serial 20 No. 22303 filed April 19th, 1915.

As shown in Fig. 2, all of the transmitter contacts are normally so connected that if the distributors at stations A and B rotate 30 in synchronism, the transmitters send only spacing impulses to the line and consequently do not effect the operation of any of the selecting magnets at the receiving station. Let us assume for example, that the 35 operator in charge of the transmitter connected to quadrant 1, desires to transmit the character "A" and also assume that the character "A" is represented by five impulses, the first two of which are marking impulses, 40 and the remaining three of which are spacing impulses. Then, to transmit the character "A," transmitter contacts 30 and 31 of quadrant 1, would be actuated so that contact 30 is moved into engagement with the negatively poled contact, and transmitter contact 31 is moved into engagement with the positively poled contact, contacts 32, 33 and 34 remaining in the positions shown in engagement with the negatively poled contacts. 45 Now as the brush 22 passes over segment 40 and connects this segment with the continuous ring 12, a negative impulse is sent over the line L, which effects the operation of polar relay 126, thereby causing contact tongue 128 to engage the negatively poled contact. Now if the distributors are 50 rotating in synchronism, brush 122 will pass over segment 140, while brush 22 passes over segment 40 and a circuit will be completed from the negatively poled contact of relay 126, contact tongue 128, ring 116, brush 122, segment 140, magnet 130 to positive battery, thereby effecting the operation of the selecting magnet 130. Now when the 55 brush 22 passes over segment 41, positive im-

pulse will be sent from the transmitter through movable contact 31, segment 41, brush 22, ring 12, line L, through the relay 126. This will cause relay 126 to move the contact tongue 128 into engagement with the 70 positively poled contact, thereby completing a circuit from said positively poled contact, contact tongue 128, ring 116, brush 122, segment 141, selecting magnet 131 to the negative side of battery. Current passing 75 through this circuit will cause the operation of selecting magnet 131. Now since the third, fourth and fifth transmitter contacts have not been actuated, spacing impulses will be impressed upon the line L as the 80 brush 22 connects the corresponding segments 42, 43 and 44 respectively with the continuous ring 12. Consequently the line relay 126 will move its pole changing tongue 128 into engagement with the negatively 85 poled contact and as the brush 122 wipes over segments 142, 143 and 144 respectively, circuits will be completed from negatively poled battery, pole changing tongue 128, ring 116, brush 122, segments 142, 143 and 90 144 and selecting magnets 132, 133 and 134 respectively to the negative side of battery. Since no current will then flow through the windings of these magnets, the magnets will consequently not be operated.

It will be seen by reason of the fact that each group of transmitter contacts is adapted when operated to provide a different combination of marking impulses, and the respective receiving mechanism being arranged to respond to the corresponding marking impulses regardless of polarity, no outside party or operator in charge of a transmitter connected to another quadrant, would be able to decipher the message transmitted unless familiar with the code employed. Furthermore, if the distributors should for some reason get out of synchronism and the impulses which are sent out by the transmitter connected to quadrant 1, 100 were, for example, received by the receiving mechanism connected to the second quadrant at the receiving station, they would be unintelligible to the receiving operator at that station by reason of the fact that the receiving mechanism at that station is arranged 105 for receiving messages of a different code.

For example, assume as before that the character "A" is to be transmitted from the transmitter connected to quadrant 1 at station A and also assume that the same transmitter contacts are actuated as referred to above, namely, contacts 30 and 31, thereby placing contact 30 in engagement with negatively poled battery and contact 31 in engagement with positively poled battery. Now assume that brush 22 is passing over the five segments of quadrant 1 at station A, and brush 122 is passing over the corresponding five segments of quadrant 2 at station B. 125 130

As the first selecting magnet of the second quadrant has one terminal normally connected to the same polarity of current as the corresponding selecting magnet of the first quadrant, that magnet will be operated in response to the first line impulses sent out from quadrant 1, but since the second selecting magnet of quadrant 2 has one terminal normally connected to current of opposite polarity to that of the second selecting magnet of quadrant 1, the second selecting magnet of quadrant 2 will not respond to the second impulse sent out by the transmitter from quadrant 1. Since the third, 10 fourth and fifth selecting magnets of quadrant 2 are connected in the same manner as the corresponding magnets in quadrant 1, and since the respective magnets of quadrant 1 were not operated by the third, fourth and 15 fifth impulses sent out from the transmitter contacts when sending the necessary impulses representing the character "A," neither will the corresponding selecting magnets connected with the second quadrant be 20 operated. Therefore, if the impulses representing the character "A" are sent out from quadrant 1, and those impulses are received by a receiving mechanism connected to the second quadrant, for which they were 25 not intended, the impulses will not effect the operation of the two selecting magnets as in the former case, but will effect the operation of only the first selecting magnet. Accordingly the first magnet would be actuated, 30 and the remaining four magnets would not be actuated which in accordance with the Baudot code would represent the character "E." Thus it will be seen that unless the message impulses sent out by a certain transmitter are received by the receiving mechanism arranged especially for their reception, 35 they will be unintelligible.

The system herein described is believed to be efficient and reliable in operation and 40 to be suitable for any class of service wherein a high degree of secrecy is desired without employing expensive and complicated apparatus. This system is believed to be suitable for Government work, where the Government 45 desires to carry on communication between various departments without having the messages received and translated by persons for whom the messages were not intended. It is also believed to be suitable for brokerage work, where different brokers may 50 each lease an arm or channel, and desire to carry on communication secretly and without having such messages become public or come into the hands of competitors.

60 What is claimed is:

1. In a telegraph system, a transmitting station and a receiving station, a current impulse distributor located at each of said stations, a transmission line connecting the said 65 stations, transmitting means connected to

each quadrant of the transmitting distributor, each of said transmitting means being arranged to send the same characters by code combinations of equal units but unlike those employed by each of the other transmitting means, and receiving means coöperating with the other said distributor to record the respective code combinations. 70

2. In a telegraph system, a transmitting station and a receiving station, a rotary distributor at each of said stations, transmitting means connected to each quadrant of the transmitting distributor, each of said transmitting means being arranged to send the same characters by code combinations unlike 75 those sent out by each of the other transmitting means, and a plurality of receiving means adapted to be associated sequentially with the respective transmitting means to record the characters transmitted. 80

3. In a multiplex telegraph system, a transmitting distributor and a receiving distributor, a transmitter connected to each quadrant of the transmitting distributor, each of said transmitters being arranged to 85 send the same characters by code combinations unlike those employed by each of the other transmitters, and receiving means associated with the receiving distributor and adapted to be connected sequentially with 90 the respective transmitting means to record the characters transmitted. 95

4. In a multiplex telegraph system, independently-driven rotary transmitting and receiving distributors divided into sections, 100 a transmission line connecting said distributors, transmitting means connected to each section of the transmitting distributor each of said transmitting means being arranged to send the same characters by code combinations composed of equal numbers of units but unlike those employed by each of the other transmitting means, and receiving means coöperating with the receiving distributor to record the respective code combinations. 105

5. In a multiplex telegraph system, a transmitting distributor and a receiving distributor, a plurality of transmitters connected to the transmitting distributor, each 110 of said transmitters having a plurality of contacts, some of which are normally connected to battery of one polarity and the remaining contacts to battery of opposite polarity, and each of said transmitters being 115 arranged to send the same characters by code combinations unlike those employed by each of the other transmitters, and receiving means coöperating with the receiving distributor to record the characters transmitted. 120

In witness whereof, I hereunto subscribe my name this 13th day of November A. D. 1917.

PAUL M. RAINES.
